UNITED STATES PATENT OFFICE.

GUSTAV HAUT, OF PERHAM, MINNESOTA.

BRICK-MACHINE.

SPECIFICATION forming part of Letters Patent No. 339,881, dated April 13, 1886.

Application filed November 30, 1885. Serial No. 184,325. (No model.)

To all whom it may concern:

Be it known that I, GUSTAV HAUT, a citizen of the United States, residing at Perham, in the county of Otter Tail and State of Minnesota, have invented certain new and useful Improvements in Brick-Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to improvements in brick-making machines, and is designed to produce a device for forming or molding moist or wet clay into blocks of suitable size and shape; and it consists in the arrangements, combinations, and constructions of parts, as hereinafter set forth, and pointed out in the claims.

In the drawings, Figure 1 represents a vertical longitudinal section of the machine, and Fig. 2 a detail perspective of the mold-box. Fig. 3 is a transverse section taken through the machine in the vertical plane indicated by dotted line $x-x$ on Fig. 1.

The main frame A has on each side an extended longitudinal timber, B. These timbers form tracks for the wheels or rollers C of the carriage D. From each side of this carriage extend pitmen E, which connect to the crank-arms F, on each end of a transverse shaft, G. Journalled in the main portion of the machine are the timbers H, which latter are interior to and parallel with the extended timbers B. On the shaft G is a bevel-pinion, I, which meshes with a bevel gear-wheel, K, supported loosely on the lower end of a vertical shaft, L, provided at its upper end, above the top of the frame, with a drive-pulley, M, by means of which the power may be applied.

The wheel K has a collar, N, with its upper edge toothed, and the shaft L carries an annularly-grooved spring-retained toothed collar, O, which normally engages with the said collar N and causes the wheel K to revolve with the shaft L, but may be moved longitudinally on the said shaft when it is desirable to stop the said wheel. As is evident, the revolving of the shaft G will cause the car-

riage to have a reciprocatory travel on the timbers B.

On the carriage rests a sliding frame having one part (designated by P) higher than the other portion, (which is designated by R,) the latter forming a seat for the mold-box S, so that the top of the said box shall be on a level with the top of the higher portion P. The box S consists of a series of compartments of the proper size and shape to form the bricks.

The main frame is covered by a platform, T, for the reception of the clay, and has at one end a downward extension or decline, U, which leads to a series of passages, V, in a frame, W, resting or supported directly over the frame supported by the carriage. At each end of this portion of the machine are erected the posts X, with slots at the upper end, as shown at Y, the said slots forming supporting guides for the transverse timber Z, from which depends the plunger A', guided, in a measure, by the box B', supported on top of the frame W. The timber Z has passing through it, near each end, a spring, C², surrounded by threaded rod C', at the upper end of which is a sprocket-wheel, D'. The said sprocket-wheels are connected by a suitable chain, and each is internally threaded so as to move on the threaded portions of the rods. One of the sprocket-wheels is provided with an operating-handle, E', so that by turning it the tension of the springs on each rod may be equally regulated. Each rod is connected by means of a pitman, F', to a wheel, G', with a series of teeth on the periphery, and pivoted to the posts X. The teeth on the wheel or pinion G' are adapted to engage with a rack-bar, H', on the carriage, the number of teeth in each being sufficient to carry the plunger A' down and up.

The top of the portion P may be metal-lined to prevent wear, and the bearing portions of the frame W may also be metal-lined. The slot V has dividing-strips I', which divide it into as many compartments as there are in the mold-box S.

At the inner end of the frame on the carriage are pawls K', which are spring-retained and cause the said sliding frame to move as the carriage is carried under the main portion of the machine. When the mold-box S has reached a point directly under the frame W, the pawls

5 K' engage with stops L' on the main frame and cause them to disengage from the carriage. The carriage is then carried on sufficiently far to cause the rack-bar H' to engage with all the teeth on the pinion G', thus forcing the plunger on the clay and compacting it into the mold-box S. The carriage then travels in the reverse direction till the stops M' thereon engage with the sliding frame and cause the said frame 10 to move with the said carriage and carry the mold-box from under the frame W, the bottom of which smooths off the top of the newly-made bricks. While the above operation is being performed, the pawls K' drop to their 15 places and the plunger is raised.

On a cross-timber between the timbers B is pivoted an upright lever, N', which is connected by means of a chain, O', passing around a pulley, P', to a lever, R', having one end bifurcated, as shown at S', and embracing the collar O, pins in the said end S' resting in the said annular groove in said collar.

Under the carriage extends a rod, T', having one end bent so as to normally engage the 25 upper end of the lever N' when the carriage has nearly approached the outward limit of its travel. The said rod moving the lever causes the clutch on the main shaft to disengage from the large gear-wheel, and thus stop the carriage. The box S may then be removed and 30 a new one substituted.

By turning the rod by means of the handle U' thereon the lever is released, the clutch falls into place, and the operation of pressing 35 the clay into the mold-box is repeated. A spring, V', causes the rod T' to assume its normal position after being operated to release the lever N'.

The spring-rods on the plunger prevent any 40 damage from stones in the clay, allowing the said plunger to give on encountering obstructions.

I claim—

1. Combined with a movable carriage, in a 45 brick-machine, a plunger having a cross-timber carrying spring-surrounded rods, toothed wheels on the plunger-supporting frames and connected to the said rods, and rack-teeth on the said carriage operating said wheels, substantially as specified.

2. In a brick-machine, a drive-shaft with a clutch-connection to the transmitting mechanism, a lever for operating said clutch, a recip-

rocating carriage, a catch on said carriage, and a lever pivoted to the frame connected to 55 the clutch-lever and adapted to engage the catch on the carriage, substantially as specified.

3. The combination, with the reciprocating carriage D, mounted and actuated substantially as described, of a sliding frame thereon 60 having an elevated floor and a depression in front of it to receive the mold-boxes, the stationary pressing-box located over said slide and provided with a plunger connected to a vertically-movable guided cross-head, the rods 65 c, vertically movable through this cross-head and bearing sprocket-wheels tapped on them and connected by an endless chain, and seated on springs, the toothed wheels G', connected by pitmen to said rods c, and the racks H' on the 70 carriage, all constructed and adapted to operate substantially as described.

4. In a brick-making machine, the combination, with the press-box, its plunger, and a carriage bearing rack-teeth, of the spring- 75 seated rods passed freely through the cross-head of the plunger, the toothed wheels actuated by said rack-teeth and connected to the said rods by pitmen, and the sprocket-wheels tapped on said rods and connected by an end- 80 less chain, substantially as described.

5. In a brick-making machine of the character described, the combination, with a press-box, a rolling carriage, and a sliding frame thereon, of the spring-actuated angular pawls 85 K', pivoted to said sliding frame, the stops M' on the end of the carriage, and stops L' on the main frame, substantially as described.

6. The combination of the carriage D, actuated by cranks on the horizontal shaft G, and 90 provided with a bent spring-actuated rod, T', the lever N' on the main frame, located as described, the clutching device on the main driving-shaft, the actuating-lever for the clutch, and the chain connecting this lever with 95 the lever N', all constructed and adapted to automatically stop the movement of the carriage at the proper times for removing the mold-boxes, substantially as described.

In testimony whereof I affix my signature in 100 presence of two witnesses.

GUSTAV HAUT.
